C. L. WRIGHT.
CHARGE SEPARATOR FOR FIXED AMMUNITION.
APPLICATION FILED JUNE 4, 1915.

1,151,643.

Patented Aug. 31, 1915.

UNITED STATES PATENT OFFICE.

CARTER L. WRIGHT, OF BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

CHARGE-SEPARATOR FOR FIXED AMMUNITION.

1,151,643.

Specification of Letters Patent.

Patented Aug. 31, 1915.

Application filed June 4, 1915. Serial No. 32,154.

To all whom it may concern:

Be it known that I, CARTER L. WRIGHT, a citizen of the United States, and resident of Bethlehem, county of Northampton, State 5 of Pennsylvania, have invented certain new and useful Improvements in Charge-Separators for Fixed Ammunition, of which the following is a specification.

This invention relates to an improved separator adapted either to separate different kinds of explosives in a cartridge case or to prevent relative movement of the particles of explosive when only one kind is used.

The object of the invention is to provide a 15 separator which is rigid in construction and embodies a minimum amount of material, and, therefore, introduces a minimum amount of foreign matter into the case.

The invention will be more particularly 20 described in connection with the accompanying drawing in which—

Figure 1 is a side view, partly in section and partly broken away, of a cartridge case and projectile; Fig. 2 is a section on the line 25 2—2 of Fig. 1; Fig. 3 shows the three parts of the separator before being assembled; and Fig. 4 illustrates the manner of assembling these parts.

Referring to the drawing 10 indicates a 30 cartridge case and 11 a projectile secured in the open end of the case, in the usual manner.

The present invention is used in connection with the larger sizes of cartridges, such as are used in rapid fire guns. As usually 35 constructed a certain amount of explosive is placed in the closed end of the case, surrounding the primer and upon this is placed a wad or diaphragm 12. The separator A extends from wad 12 to the base 13 of the 40 projectile and it is preferably constructed of three rectangular pieces of cardboard or equivalent material as illustrated in Figs. 3 and 4. The section 14 has two slits 14^a in one end and extending throughout half its 45 length, the slits being at the sides of the section and parallel with its edges. The section 15 has similar slits 15^a at its other end. The sections 14 and 15 are identical in structure, but used in reverse positions when assembled. The section 16 has a slit 16^a at one end extending parallel to and near one side of the section and a similar slit 16^b at the other end and extending parallel to

and near the other side. The three sections of the separator are assembled as illustrated 55 in Fig. 4 the uncut end of each of the sections 14 and 15 being within a slit of the other section and respectively within the slits 16^a and 16^b. This forms a triangular structure which is strong and rigid in proportion to the amount of material used and, as shown in Fig. 2, it substantially divides the forward portion of the cartridge case into several compartments which may be used for different kinds of explosive material or in which the same kind of explosive material may be placed, the separator preventing shifting of the charge and attrition between the particles.

The separator A is preferably made as 70 large as will permit of its being inserted through the smaller open end of the cartridge case and long enough to extend from the base of the projectile to the wad 12. The slits are made narrow so that the sections 75 will fit in them rather tightly and the article as a whole can be readily handled without danger of the sections separating.

By the use of the triangular or three-piece separator I obtain a maximum of strength 80 with a minimum of material and reduce the weight of inert or non-explosive material in the cartridge to a minimum and also the amount of smoke produced, which is desirable when using smokeless powder.

Having thus described my invention what I claim and desire to secure by Letters Patent is:—

1. A separator for use in a cartridge case comprising three sections interlocked near 90 their edges and forming a structure which is triangular in cross section.

2. A separator for use in a cartridge case comprising three rectangular sections of cardboard provided with longitudinal slits 95 and interlocked, substantially as described.

3. A separator for use in a cartridge case comprising a section having parallel slits extending inward from one end thereof, a section having parallel slits extending inward 100 from the other end thereof, and a section having a slit extending inward from each end thereof, said sections being assembled to form a rigid triangular structure, substantially as described.

4. The combination with a cartridge case

and projectile, of a separator for powder comprising a triangular cardboard structure arranged within a cartridge case at the rear of the projectile.

5. The combination with a cartridge case and a projectile secured in the open end thereof, of a separator for powder comprising

ing a triangular cardboard structure arranged within the cartridge case in the rear of the projectile, and a transverse partition 10 or wad within the cartridge case in the rear of said separator.

In testimony whereof I affix my signature.

CARTER L. WRIGHT.
